UNITED STATES PATENT OFFICE.

JOHANNES MARINUS VAN DER POEL, OF EINDHOVEN, NETHERLANDS, ASSIGNOR TO
GENERAL ELECTRIC COMPANY, A CORPORATION OF NEW YORK.

EXHAUST MACHINE.

Application filed April 8, 1926, Serial No. 100,708, and in the Netherlands June 2, 1925.

This invention relates to exhaust machines of the type which has an intermittently rotating carrier for the vessels to be exhausted, and a number of high vacuum pumps moving with the carrier, the heads or holders for the vessels to be exhausted being attached to the carrier and each head connected to a high vacuum pump. Exhaust machines of this general type have been used, especially in exhausting incandescent lamps, radio tubes, and other electrical apparatus, the vessel to be exhausted being directly connected to the high vacuum pump during the entire process of exhaust. Usually a reservoir or buffer chamber common to all the high vacuum pumps is inserted between them and the rough vacuum piping to act as a backer for the high vacuum pumps and preserve the vacuum. One drawback of such exhaust machines is that when a leaky vessel is being pumped the exhaust of all the other vessels in the device becomes very difficult. The present invention overcomes this difficulty by providing means to connect the backer pipe between each high vacuum pump and its backer or rough vacuum pump separately to the rough vacuum pump before the final exhaust is started, and then to seal air tight the backer pipe of each pump during final exhaust.

According to the invention the backer pipes of the high vacuum pumps are connected to a valve disc which moves with the rotatable carrier and which cooperates with a stationary valve seat in such a way that in at least one position of the rotatable carrier the backer pipe of each high vacuum pump is connected to the backer or rough vacuum pump. By keeping the backer or rough vacuum sides of the high vacuum pumps entirely separated from each other, a leaky vessel on the exhaust machine cannot have any detrimental effect upon the other vessels which are then being exhausted on the machine. Also it is no longer necessary to insert valves between the vessels to be exhausted and the high vacuum pumps. Preferably only one vessel to be exhausted is connected to each high vacuum pump in an exhaust machine embodying this invention.

Of course the air which is pumped out of the vessels to be exhausted by the high vacuum pumps after the backer pipes are closed will tend to increase the pressure of

the backer vacuum, but in accordance with the invention the volume of the backer vacuum pipe between the high vacuum pump and the valve disc is made so large that the pipe serves the purpose of a backer vacuum preserver which keeps the backer vacuum pressure below the maximum at which the high vacuum mercury vapor jet pumps commonly used begin to operate uneconomically. Also in accordance with the invention the backer vacuum pipes are formed as large spirals or helices, which may be cooled by the cooling water of the pump or they may be placed entirely outside of the pump. In case a high vacuum mercury vapor jet pump should be connected directly to the atmosphere on account of a leak in the vessel to be exhausted the mercury in the pump would begin to bubble very strongly, and would tend to pass up into the backer vacuum pipe. By making these pipe connections large the liquid mercury that drops back and the mercury vapors that rise will be able to pass each other, and the danger of air pockets in the backer vacuum pipe will be avoided. The pipes should be cooled in order to condense any mercury vapor sucked thru with the air.

At the start of the process of exhaustion the backer vacuum pipes of the high vacuum pumps may also be connected to the shop vacuum system, but it will generally be better to connect the backer vacuum pipe to a rough vacuum pump in order to insure a good vacuum on the backer vacuum side of the high vacuum pumps at the start of the exhaust process, as in that case if metal vapor jet pumps are used these pumps need not be heated as much as though the backer vacuum were poor, and, therefore, will work more economically than usual.

The valve system of the exhaust machine may, in accordance with the invention, be made with a rotating valve disc provided with as many ports as there are high vacuum pumps on the exhaust machine, the backer vacuum pipes of the high vacuum pumps terminating at these ports, and a stationary valve seat fitting air tight to the rotatable valve disc and having one or more ports connected to rough vacuum pumps and registering with the ports in the rotating valve disc when the intermittently rotating carrier is standing still. To prevent leakage into the valve, one or more annular slots

may also be made in the contacting surfaces of the valve disc and valve seat to surround the ports in the surfaces, these slots being connected to a vacuum pump.

5 In the attached drawing which shows one form of exhaust machine embodying the invention and adapted for exhausting the bulbs of incandescent lamps, and similar articles, Fig. 1 is a plan view of the machine; Figure 2 is a vertical section along the line 11-11 in Figure 1; Figure 3 is a vertical section of the mercury vapor jet or condensation pump which serves as the high vacuum pump in the exhaust machine, and Figure 4 and 10 Figure 5 are respectively a vertical section and a plan of the valve used in the machine 15 shown in the drawing.

The particular machine shown in the drawing is assembled on a table 1 supported on legs 2. The carrier 3 can rotate on the table 1 on a ball bearing 4. This rotatable carrier has a hub 5 at the center which is rigidly attached to a central tubular shaft 6, which constitutes an extension of another 20 tubular shaft 49 screwed to this shaft and carries a rotatable valve disc 7 at its top (Fig. 2). The stationary valve seat 8 attached to a yoke 9 seats on this rotatable valve disc 7. A number of exhaust heads 10 25 are provided on the rotatable carrier to make air tight connections between the exhaust tubes of the bulbs to be exhausted and the high vacuum tubing. A protecting disc 11 is placed over these heads which is attached to the rotatable carrier 3 by means of bolts 30 35 12. (Fig. 2).

Each head 10 is connected to the exhaust pipe 25 of a mercury vapor condensation pump by means of high vacuum tubing 23 40 (Fig. 2). The mercury vapor condensation pump is provided with a boiler 26 (Fig. 3) for the mercury, or other metal with low melting point, and a heating coil 27 is placed inside of the boiler. The mercury vapor 45 produced by the heating passes up thru the vapor conduit 28 and is deflected thru the holes in this conduit downward thru the ring shaped jet nozzles 29 and 30. The mercury vapor thereby takes the air molecules 50 from the vessel to be exhausted along with it thru the exhaust pipe 25 and condenses against the wall of the pipe 25. The liquefied mercury drops into the chamber 31 from 55 which it is drained into the supply tubes 32 and 33. The air that was drawn by the vapor is sucked off thru the spiral pipe 34 which leads out of the cover plate of the chamber 31. To speed up the condensation of the mercury vapor the pipe 25 and the 60 spiral tube 34 are surrounded by a water jacket 35 thru which the cooling liquid, for instance water, may be made to flow. The boiler 26 is surrounded by a heat insulating cover 36.

65 The backer vacuum pipe 38 (Fig. 2) is a

continuation of the spiral tube 34 and in order to increase its volume part of it is wound as a spiral. The backer vacuum pipe is connected air tight to the rotating valve disc 7 (Fig. 5) which is attached to the tubular 70 shaft 6 by means of a set screw 39 (Fig. 4). The air tight connection between the backer vacuum pipe and the valve disc 7 may be made by means of a gasket 40, made of rubber or similar elastic product, which is 75 pressed around the pipe 38 by means of a nut 41.

When the carrier 3 revolves intermittently, taking the valve disc 7 along with it, the backer vacuum pipe 38 comes into position opposite a port 42 in the stationary valve seat 8. This port is connected to a rough vacuum pump or to the rough vacuum piping of the shop through a rough vacuum pipe 44. In all other positions the port 42' 80 of the valve disc 7 is closed by the blank surface of the stationary valve seat 8 and the backer vacuum sides of the metal vapor condensation pumps 31 in those positions constitute an enclosed space.

85 In order to obtain a good air tight fit of the valve the stationary valve disc 8 is provided with a ring shaped slot 45 (Fig. 5) which is connected to a vacuum pump by means of a port 46.

90 The cooling water is supplied to the jacket 35 of the metal vapor condensation pumps by means of the inlet pipe 50. This pipe has a water tight connection with the intermittently rotating shaft 49 and terminates in a 100 chamber in this shaft. From this chamber the water supply pipes 51 take the water to the jackets 35. The water is drained thru the outlet pipes 52 into a stationary tank 53 from which it can be removed. This tank 105 may as a matter of convenience be mounted on pedestals 54.

95 The carrier can be made to rotate intermittently in the usual way by well known mechanism not shown in the drawing, and of which only a gear 68 is indicated, which may be driven by an electric motor. The shaft of this gear carries an arm 69 on the end of which there is a roller 70 meshing in the slot 71 of the carrier 3 to rotate the carrier intermittently.

100 The drawing shows a practical embodiment of the invention in which seven exhaust heads are placed on the rotatable carrier, each one of which is directly connected to the high vacuum side of a metal vapor condensation pump. Therefore, also seven metal vapor condensation pumps rotating with the carrier 3 have been provided. The 110 seven positions of the carrier are marked A, B, C, D, E, F, and G (Fig. 1) and the seven positions of the rotatable valve disc 7 corresponding to those of the carrier 3 are marked with the corresponding letters (Fig. 5). In the position A of carrier 3 a bulb to 115

be exhausted is placed with its exhaust tube in a head 10. In the position B the backer vacuum pipe of the corresponding condensation pump is connected to the port 42 of the stationary valve disc 8. The backer vacuum space of the pump is exhausted and the condensation pump starts to operate. It should be noted that the condensation pumps must be designed as shown in Figure 3 of the drawing to operate both when full of air and when the backer vacuum side is suddenly connected to a good vacuum. A large amount of vapor will suddenly be formed when the backer vacuum side of the pipe is connected to the rough vacuum pump 44, but the metal vapor or the condensate are prevented from being taken along into the backer pipe by the annular chamber 31 in which an appreciable amount of liquid metal can collect, and also by the spiral backer vacuum pipe which is placed inside a water cooled jacket. If metal vapor should enter the tubing 34 it will be condensed there and it will drop back into the annular chamber 31.

In the position B the bulb to be exhausted is enclosed by an oven 81. This oven is attached to the table 1 and is provided with gas burners 82 and 83.

In the positions C, D, E, F and G the port 42' of the backer vacuum pipe 38 is closed by the blank surface of the stationary valve seat 8. The backer vacuum side of the high vacuum pump is now closed. Gases exhausted from the bulb by the metal vapor jets are delivered to the backer vacuum pipe and accumulate in the backer pipes 34 and 38. Of course, care has to be taken to make the volume of the backer pipes 34 and 38 great enough so that the gases which accumulate in the closed backer pipes during the final exhaust of the lamp or similar vessel do not cause the backer pressure in those pipes to exceed the backer pressure at which the high vacuum pump no longer operate satisfactorily. On the other hand, however, it is desirable to use a high vacuum pump which can operate against a rather high backer vacuum pressure, such as the mercury vapor condensation pump of Fig. 3, which has two annular nozzles in series. This type of high vacuum pump can operate satisfactorily even against a backer vacuum pressure of about 20 mm. of mercury. Considerations of economy, however, makes it necessary to keep the backer vacuum pressure of the movable high vacuum pumps as low as possible, and, therefore, it is advisable to exhaust the backer vacuum pipes of the movable high vacuum pumps thoroughly when they are in the position B.

Red phosphorus is often used in vacuum lamps to improve the vacuum of the lamp. The phosphorus is introduced, for instance, by either dipping the filament in a suspen-

sion of phosphorus or by spraying it on the filament. When such lamps are being exhausted some vapor of phosphorus is always carried along, and partially condenses in the mercury vapor nozzles of the mercury vapor condensation pumps, partially clogging the nozzles, and causing bad operation or no operation at all of the pump. Therefore, the metal vapor condensation pumps should be made so as to be cleansed internally very easily, as, for example, by making the cups 29 and 30 of Fig. 3, where the nozzles point downward, removable.

In the position G the bulb is sufficiently exhausted and can be sealed off. After this the lamp can be removed by hand or mechanically and after having removed the sealed off exhaust tube a new lamp can be inserted in the head 10.

What I claim as new, and desire to secure by Letters Patent of the United States, is:

1. An exhaust machine comprising an intermittently rotatable carrier having a plurality of exhaust heads, an equal number of final pumps mounted on and movable with said carrier and each directly connected to a corresponding exhaust head, a rough pump to act as a backer for said final pumps, backer pipes on the outlets of said final pumps, and means for connecting each backer pipe in succession to said rough pump and then sealing said pipe from said rough pump at a point remote from said final pump whereby each final pump discharges into an evacuated reservoir formed by said sealed backer pipe.

2. An exhaust machine comprising an intermittently rotatable carrier having a plurality of exhaust heads, a plurality of final pumps mounted on and movable with said carrier and each directly connected to a corresponding exhaust head, a rough pump to act as a backer for said final pumps, backer pipes on the outlets of said final pumps, and a valve rotatable with said carrier for connecting said rough pump to each backer pipe at a point remote from said final pump and in at least one position of said carrier and sealing said backer pipe from said rough pump in subsequent positions of said carrier.

3. An exhaust machine comprising an intermittently rotatable carrier having a plurality of exhaust heads, a plurality of final pumps mounted on and movable with said carrier and each directly connected to a corresponding exhaust head, a rough pump to act as a backer for said final pumps, backer pipes on the outlets of said final pumps large enough to act as backers for said final pumps when evacuated by and sealed off from said rough pump, a rotary valve disc movable with said carrier and having a plurality of ports corresponding to said final pumps and connected to said

- backer pipes at points remote from said final pump, and a valve seat cooperating with said valve to connect each of said ports to said rough pump at one position and to seal said port at subsequent positions of said carrier.
4. An exhaust machine comprising an intermittently rotatable carrier having a plurality of exhaust heads, a plurality of final pumps mounted on and movable with said carrier and each directly connected to a corresponding exhaust head, a rough pump to act as a backer for said final pumps, backer pipes of large diameter shaped into a helix and connected to the outlets of said final pumps, and a valve rotatable with said carrier to control at points remote from said final pumps the connections between said rough pump and said backer pipes to connect each backer pipe to said rough pump in one position and to seal it in subsequent positions.
5. An exhaust machine comprising an intermittently rotatable carrier having a plurality of exhaust heads, a plurality of final pumps mounted on and movable with said carrier and each directly connected to a corresponding exhaust head, a rough pump to act as a backer for said final pumps, a backer pipe connected to the outlet of each final pump and of sufficient capacity to preserve when exhausted and sealed a backer vacuum during exhaust by the final pump of the vessel in the exhaust head, and a valve between said backer pipes and said rough pump having ports connected to said backer pipes and actuated by said carrier to first connect each backer pipe to the rough pump and subsequently seal said pipe at a point remote from said final pump during the exhaust of said vessel by the final pump.
6. An exhaust machine comprising a movable exhaust head, a final pump connected directly to and movable with said head and discharging into a backer pipe of sufficient capacity when exhausted to act as a backer for the final pump, a stationary rough pump, and means actuated in synchronism with said head to automatically connect said pipe to said pump during a portion of the travel of said head and to seal said pipe at a point remote from said final pump during the remainder of the travel of said head.
- In witness whereof, I have hereunto set my hand this twenty-fourth day of March, 1926.

JOHANNES MARINUS van der POEL.
